UNITED STATES PATENT OFFICE.

CLABORN F. MOON, OF FRANKLINVILLE, NORTH CAROLINA, ASSIGNOR OF ONE-HALF
TO ARLIN R. LEWIS, OF GREENSBORO, NORTH CAROLINA.

ADJUSTABLE GEAR WHEEL.

Application filed February 17, 1927. Serial No. 168,977.

My invention relates to certain improvements in gear wheels and more particularly to gear wheels capable of repair or adjustment and primarily adapted for use in connection with looms, altho the invention is of course not limited to use in looms alone, as it is adapted for a wide range of utilities. An object of my invention is to provide a gear wheel for looms having separable hubs to which the gear wheel may be adjustably secured in any desired position, so that when one portion of the gear wheel has been worn another portion of the gear upon which the greatest strain is placed may be presented. Another object of my invention is to provide a gear wheel which is adapted to be placed on the pick shaft and crank shaft of looms, said gear wheel having a separate hub which is capable of any desired adjustment with relation to the gear wheel.

It is a well known fact that most of the wear upon the teeth of the crank-shaft gear in looms is at the point of contact with the comb-shaft gear at the time the loom makes the "pick". When the few teeth at the point are worn the gear has either to be taken from the shaft re-key-seated and fitted in a new position, or in the case of some improvements the gear is separated from the hub and adjusted in a new position.

I am aware that heretofore gear wheels have been used in looms in which the gear wheel itself is capable of adjustment with relation to the hub, but in all instances there are only from four to six positions of adjustment between the gear and the hub, this adjustment is effected by means of bolts penetrating different holes in the gear and hub. In my invention I have devised means whereby the gear may be adjusted with relation to the hub to any desired position and when once adjusted will remain in adjusted position.

Some of the objects of my invention having been stated, other objects will appear as the description proceeds, when taken in connection with accompanying drawings, setting forth a preferred embodiment of my invention, in which—

Figure 1 is a vertical cross-sectional view taken through my improved loom gear for Draper looms;

Figure 2 is a vertical cross-sectional view taken through my improved crank shaft gear for Draper looms;

Figure 3 is a view taken along the line 3—3 in Figure 2 looking in the direction indicated;

Figure 4 is an elevation of my improved Draper loom gear taken along the line 4—4 in Figure 1;

Figure 5 is an elevation taken along the line 5—5 in Figure 1 looking in the direction indicated;

Figure 6 is a vertical cross-sectional view taken through my improved loom gear for 65 Stafford looms;

Figure 7 is a cross-sectional view taken through my improved crank shaft gear for Stafford looms;

Figure 8 is an elevation taken along the 70 line 8—8 in Figure 7 with the friction pulley removed;

Figure 9 is a modified form of Figure 2 showing the use of set screws instead of tapered pins.

A brief description of the drawings having been given, a detailed description of the same will now follow in which like reference characters indicate corresponding parts throughout the drawings.

In Figure 1 I have shown a hub member 10 which is adapted to be keyed to the pick shaft of a Draper loom by having the proper key inserted in the groove 11. This hub member 10 has a plurality of holes 12 placed around a circle which has its center at the center of the hub. This hub 10 has a T-shaped, annular groove 13 therein in which the bolts 14 are adapted to be inserted through the hole 15 in a hub 10. A set screw 16 is also placed in hub 10 by means of which the hub may be secured on the shaft if the key arrangement is not desired.

The loom gear 17 is adapted to fit against the side of hub 10 and has a plurality of holes therein through which the bolts 14 are adapted to pass, and on the ends of the bolts 14 are the nuts 18. The loom gear 17 has a plurality of holes arranged around the same, said holes meshing with the holes 12 in the hub member 10. Tapered pins 20 are adapted to be inserted through the holes in the gear 17 and into the holes 12 in the hub member 10.

In the crank shaft gear for Draper looms, I provide the pulley 21 having the hub portion 22, and over this hub portion 22 the crank shaft gear 23 is adapted to fit. This crank shaft gear has a circular T-shaped slot 24 in which the bolts 25 are adapted to fit. These bolts 25 are inserted into the T-shaped slot 110

through the hole 26 in the gear wheel, and when the bolts are inserted into the T-shaped slot through the hole 26 they may be slid around to any desired position as shown in 5 Figure 3.

Located at a constant distance from the center of the crank shaft is a plurality of holes 27 in which the tapered pins 28 are adapted to be inserted, and the pulley 21 likewise has a plurality of holes matching with the holes 27 in the crank shaft gear into which the pins 28 project after passing through the holes 27 in the crank shaft gear. The bolts 25 have nuts 29 thereon, and by 10 means of the nuts 29 the bolts 25 may be rigidly secured in position and firmly bind the crank shaft gear 23 to the pulley 21 and the pins 28 preserve this adjustment. In case the tapered pins 28 are used as above set forth it 15 is of course apparent that the number of adjustments of the crank shaft 23 with relation to the pulley 21 is limited, but should it be desired the pins 28 may be dispensed with and the holes in the pulley 21 omitted and the set 20 screws 30 be substituted, and in this case when the crank shaft gear 23 is adjusted to the desired position with relation to the pulley 21 the set screws 30 may be driven home and their points will embed themselves 25 in the surface of the pulley 21 and prevent the adjusted relation from being changed except when desired.

Or in case it should be desired, I can use both the tapered pins and the set screws as 30 is clearly shown in Figure 4. In Figure 4 the set screws 30^a may be used for the purpose of adjusting the angular relation between the hub member and the gear member.

In Figures 6, 7, and 8 I have shown a preferred embodiment of my invention as it relates to the Stafford loom. In my improved loom gear for Stafford looms I have the hub member 40 which is adapted to be secured to the pick shaft by any suitable means such as 40 a key being placed in the slot 41, and in the hub member 40 I have the T-shaped slot already described for the Draper loom which has bolts 43 adapted to be inserted therein through the hole 44, and placed in a circle 45 whose center is the center of the pick shaft is a plurality of holes in which the tapered pins 45 are adapted to be inserted, which pins penetrate corresponding holes in the gear member 46. Or if desired, the tapered pins may 50 be dispensed with and set screws 47 may be used. In case set screws are used exclusively these set screws will be pointed in a manner similar to the set screw 30 in the Draper structure. In case both the set screws and pins 55 are used, the pins 45 will be used for maintaining the parts in adjusted position and the set screws 47 will be used for the purpose of adjusting angular relation of the gear 46 to the hub member 40.

60 The bolts 43 have nuts 48 thereon, which

when tightened hold the parts 40 and 46 in adjusted position. The gear member 46 has the gears 49 and 50 thereon.

In the Stafford crank shaft gear there is the brake wheel 60 having the hub portion 61, 70 only a portion of the brake wheel 60 being shown, as this is the conventional brake wheel. Brake wheel 60 has a plurality of holes placed at an equal distance from its center in which the bolts 62 are adapted to be placed. Fitting against the brake wheel 60 is the crank shaft gear 63 which has a T-shaped circular slot therein, similar to the T-shaped slots previously described in which the heads of the bolts 62 are adapted to fit by being inserted therein through the hole 64. Located at an equal distance from the center of the crank shaft is a plurality of holes 65 in which the tapered pins 66 are adapted to fit, and in the brake wheel 60 is likewise located a plurality of holes which match with holes 65 in the gear wheel through which the pins 66 are also adapted to fit. Altho I have not shown set screws in Figure 7 yet I desire it to be understood that the set screws 68 may be used in this structure as well as the structure previously described.

On the face of the crank shaft gear opposite the portion which fits against the brake wheel are the projections 70, 71, 72, and 73, which have holes therein threaded to receive the stud bolts 74, which stud bolts penetrate the friction pulley 75 and secures the friction pulley to the crank shaft gear. Only a portion of this friction pulley is shown as it is the conventional friction pulley used in the Stafford loom. The hub member of the brake wheel 60, which is designated by the numeral 61, may be secured to the crank shaft by means of a key inserted in the groove 76 and fitting in a corresponding groove in the crank shaft which is not shown.

The method of operation of my device is as follows: The hub portion of any one of these devices is secured to the proper revolving shaft and the gear wheel is placed next to the hub portion, the bolts are placed in the T-shaped slots and through the holes in the gear members, and while the bolts are loose the gear member may be rotated with relation to the hub member to any desired position, and when the nuts are driven home on the bolts the gear member is securely held to the hub member. In order to make assurance doubly sure that the gear member and the hub member will remain in adjusted position, the tapered pins may be driven through the corresponding holes in the hub and gear members, or if desired, the tapered pins may be dispensed with and the set screws used instead, the set screws giving an indeterminate number of adjustments, or if it is desired to use both the pins and the set screws, the set screws may be used to adjust the gear wheel 125 with relation to the hub member so that the 130

gear wheel will run true and the pins may also be used for retaining the parts in adjusted position.

In the drawings and specification I have set forth a preferred embodiment of my invention, and altho specific terms are employed that are used in a generic and descriptive sense only, and not for purposes of limitation, the scope of the invention being set forth in the appended claims.

I claim:

1. In an adjustable gear, a hub member, a gear member, holes penetrating one of the members, a circular T-shaped slot in the other member, bolts having their heads mounted for adjustment in the T-shaped slot and having their shanks positioned in the said holes, and nuts on the smaller ends of the bolts for securing the gear member and hub member together in any desired adjusted relation to each other, a plurality of tapered holes penetrating both the gear member and hub member at points equidistant from the center of the gear and hub members, a plurality of tapered pins adapted to be driven in the tapered holes to insure the parts retaining their adjusted relation to each other.

2. In an adjustable gear, a hub member adapted to be fixedly secured to a rotatable shaft, a gear member adapted to fit against the side of the hub member, a circular slot extending around the hub member, said circular slot being T-shaped in cross section, a

plurality of bolts adapted to have their head portions slidably secured in the T-shaped slot, a plurality of holes in the gear member in which the tip portions of the bolts are adapted to be secured, nuts on the ends of the bolts, a plurality of tapered holes piercing both the gear member and the hub member at points equidistant from the center of the gear and hub members, and a plurality of tapered pins adapted to be driven in the tapered holes to hold the gear and hub member in adjusted position.

3. In an adjustable gear, a hub member, a gear member, holes in one of the members, a circular T-shaped slot in the other, bolts loosely mounted in the T-shaped slot and having their heads disposed in the larger portion of said slot and having a portion of their shanks positioned in the contracted portion of the slot, and having a more remote portion of their shanks extending through the said holes and nuts threadably engaging the tips of the bolts for securing the hub and gear together in any desired adjusted relation, a plurality of tapered holes penetrating the gear and hub members, said holes being located at points equidistant from the center of the gear and hub members and a plurality of tapered pins adapted to be driven home in the tapered holes to insure the retention of the adjusted relation between the gear and hub members.

In testimony whereof I affix my signature.

CLABORN F. MOON.
